UNITED STATES PATENT OFFICE

2,383,912

WINDOW STRUCTURE

Giuseppe Gargiulo, Miami, Fla., assignor to Super Vent Window Company, Miami, Fla., a corporation of Florida

Application March 19, 1941, Serial No. 384,031

14 Claims. (Cl. 189—67)

This invention relates to window structures with particular reference to the operating mechanism and has for an object to provide mechanisms for moving horizontally disposed window sections into opened and closed positions by a combination of sliding and swinging movements, and by swinging movement alone.

Another object is to provide such mechanism in which the parts are so connected and relatively disposed that the opening and closing movements are accomplished with very little effort and strain upon the elements.

Another object consists in providing such mechanism in which the elements acting upon the window sections are adapted to move and be housed within window frames of standard size and shape.

Another object consists in providing such mechanism in which the elements are so arranged, proportioned and connected that, immediately following the initial stage of the opening movement, there is a balance established which greatly facilitates and reduces the strain of continued opening movement.

Another object consists in providing such mechanism in which the window sections are very tightly closed and automatically locked in closed position by the normal operation of the parts.

Another object consists in providing such mechanism which is particularly well suited to association with a complete window frame so that a unitary structure results that is well adapted for bodily shipment and installation in connection with the construction of buildings, as distinguished from the successive installation of a plurality of parts.

Another object consists in providing such mechanism in which the top frame member of a window section may be employed as a means for transmitting the opening movement activity at one side of the window frame to the other side thereof, thereby enabling a substantial reduction in the number of operating elements at said other side of the window frame.

Another object consists in providing such mechanism in which the manually operated power elements may be small in size and compact in arrangement with the result of reducing bulk, weight, and space occupied, and improving appearance while maintaining efficient operation.

A further object consists in providing certain improvements in the form, construction, material and arrangement of the several parts whereby the above named and other objects may effectively be attained.

Practical embodiments of my invention are

represented in the accompanying drawings, in which

5 Fig. 1 represents a broken face view, partly in section, of a complete unit embodying my invention;

Fig. 2 represents a horizontal section taken in the plane of the line II—II of Fig. 1 looking in the direction of the arrows;

10 Fig. 3 represents a vertical section taken in the plane of the line III—III of Fig. 1, looking in the direction of the arrows, with the parts in closed position;

Fig. 4 represents a view similar to Fig. 3 with the parts in open position;

15 Fig. 5 represents a detail side elevation, partly in section, showing a modified form of manual actuating mechanism; certain of the parts being shown in different positions in full and dotted lines;

20 Fig. 6 represents a detail side elevation, partly in section, showing a second modified form of manual actuating mechanism; certain of the parts being shown in different positions in full and dotted lines;

25 Fig. 7 represents a detail side elevation, partly in section, showing a modified form in which a window section itself transmits the actuating power from one side of the window frame to the other; certain of the parts being shown in different positions in full and dotted lines;

Fig. 8 represents a detail side elevation, partly in section, showing a modified form of elements connecting and operating the window sections; certain of the parts being shown in different positions in full and dotted lines;

30 Figs. 9 and 10 represent detail side elevations, partly in section, showing a second modified form of elements connecting and operating the window sections, with the parts in closed and open positions respectively;

35 Fig. 11 and 12 represent detail side elevations, partly in section, showing another modified form of elements connecting and operating the window sections particularly adapted to constructions wherein the framing is composed of wood, plastics, molded fibrous materials and compositions or the like, with the parts in closed and open positions respectively;

40 Fig. 13 represents a horizontal section taken in the plane of the line XIII—XIII of Fig. 11, looking in the direction of the arrows.

45 Referring to the form shown in Figs. 1 to 4 inclusive, the window frame comprises hollow elements including a sill 1, a top 2, and side members 3, 4. These elements may be composed of

any suitable material but are preferably metallic. Within the window frame is located a pair of window sections having panes 5, 6, mounted in rectangular rims composed of top and bottom members 7, 8, and side members 9, 10. The rims of the window sections may also be composed of any desired material, but preferably consist of metal. While I have shown a pair of window sections, it will be evident that any suitable number may be embodied in the window unit, and that the panes may be either transparent or translucent glass or consist of any other desired material including opaque substances.

The operating mechanism comprises a cross shaft 11 that is located within the hollow sill 1 and has its ends mounted in bearings 12, 13. Arms 14, 15 have their lower ends pinned, keyed, or otherwise suitably fixed to the extremities of shaft 11 and their upper ends pivoted to the lower ends of links 16, 17, which links have their upper ends pivoted to slides 18, 19, respectively, that are housed in the window frame side members 3, 4.

Arm 15 also has its upper end pivoted to the lower end of a short link 20 which has its upper end pivoted to the extremity of a power arm 21 that is suitably fixed to a worm gear 22 which is journaled at 23 in a housing 24 which is formed on or secured to the lower part of the window frame and is in open communication with the side member 4 and the adjacent portion of the sill 1. The said worm gear 22 meshes with a worm 25 that has bearings 26 mounted in the lower part of housing 24, which bearings may be fitted with any appropriate form of adjustment in order to obtain and maintain satisfactory engagement with the worm gear 22. The worm 25 is keyed, or otherwise fixed, to a short shaft 27 which projects inwardly through the wall of housing 24 and carries a manual operating crank 28 for turning the worm and hence actuating the worm gear and connected parts.

The lower window section has a pair of arms 29, 30 rigidly secured at the top 7 of its rim, which arms have their free ends pivoted at 31, 32 in the slides 18, 19 for movement therewith. It will be seen by reference to Figs. 3 and 4 that these pivots 31, 32 are not located on the vertical central line of slides 18, 19, but are slightly to the rear thereof. Straps 33, 34 are pivoted at 35, 36 to the upper portions of the side members 9, 10, respectively, of the window section rim, and at 37, 38 to the window frame side members 3, 4. The said pivots 31, 32 lie in slots 39, 40 formed in slides 18, 19, respectively, so that the pivots 31, 32 remain in fixed position regardless of the movement of the slides. As clearly shown in Figs. 3 and 4, the pivots 31, 32 and slots 39, 40, like the pivots 31, 32, do not coincide with the center line of the slides 18, 19, but are positioned somewhat to the rear of said line. This arrangement provides for a better balancing of the moving parts in order to facilitate and reduce the force required for and strain of the opening movement after the same has been initiated.

As the upper window section is mounted and connected with the slides 18, 19 in exactly the same way as the lower window section, it is regarded as unnecessary to repeat the description in connection with the upper window section.

In operating the form of construction shown in Figs. 1 to 4 inclusive, and assuming the parts to be in closed position as indicated in Figs. 1

5 to 3 inclusive, the crank 28 is turned so as to actuate the worm and gear and thereby swing power arm 21 in a counter-clockwise direction toward its position shown in Fig. 4. Through its connection with link 20, this movement of power arm 21 breaks the toggle formed at one side of the window frame by links 15, 17 and, through the connection established by shaft 11, 10 breaks the toggle formed at the other side of the window frame by links 14, 16. This movement causes links 16, 17 to pull downwardly on slides 18, 19, which movement of the slides correspondingly imparts downward movement to pivots 31, 32 on arms 29, 30 which, at first, slides the lower window section downwardly and then, through the effect of straps 33, 34, causes it to swing outwardly and upwardly on pivots 31, 32. This movement continues until substantially the full length of slots 39, 40 has traversed fixed pivots 37, 38 and the parts have reached the position illustrated in Fig. 4.

As will be seen by examination of the upper portion of Fig. 3, the arms 29, 30 are almost, but not quite, in line with the straps 33, 34 when the parts are in closed position, and the initial downward movement imparted to the pivots 31, 32 of the arms 29, 30 at once increases the relative angularity of the arms 29, 30 and straps 33, 34. This action is greatly facilitated by the off-center location of pivots 31, 32 and 30 37, 38 because such location, in effect, increases the length of arms 29, 30 and straps 33, 34, thereby adding to the effective gravitational downward pull of the slides and attendant parts, which pull, so to speak, in large part balances the window section forwardly and rearwardly of pivots 35, 36 because pivots 37, 38 are fixed in the frame while pivots 31, 32 move downwardly with slides 18, 19 and turn the window section 40 on pivots 35, 36 at the same time that arms 29, 30 are turning on pivots 31, 32.

When it is desired to close the window from the positions shown in Fig. 4 to those shown in Fig. 3, it is merely necessary to turn crank 28 in the reverse direction, whereupon slides 18, 19 45 will push upwardly on pivots 31, 32 and, by imparting a combined sliding and swinging movement to the window sections, will bring them into snug parallelism with the window frame and with the outer flanges 41 on the rims of the window sections overlapping the window frame while the said flange on the upper window section overlaps the adjacent flange on the lower window section. I prefer to proportion and arrange the parts so that links 15 and 17 on one side and links 14 and 16 on the other side have their common pivots thrown slightly to the rear of a direct line between the extremities of said links when the parts are in closed position as represented in Fig. 3. This slight throw past center forms a toggle lock for holding the window sections snugly closed. If desired, a rain shield 42 may be secured to the top of the window frame in order to protect the crack between the upper part of flange 41 and the frame against the ingress of water.

The modified form shown in Fig. 5 is the same as the form shown in Figs. 1 to 4 inclusive except that the worm gear 22 has a spur gear 43 fixed thereto which meshes with another spur gear 44 mounted in bearings in the housing 24 and engaging a rack 45 formed in the adjacent edge of slide 19. The rotation of gear 44 will, of course, move the slide upwardly or downwardly 70 according to the direction of said rotation, and

this movement is imparted to the elements at the opposite side of the window frame by toggle links 46, 47 which are pivoted to the lower end of the slide 19, to the extremity of shaft 11, and to each other. Corresponding toggle links are, of course, located and similarly connected at the opposite side of the window frame. The manner of operating this modified form is so like that of the form shown in Figs. 1 to 4 inclusive, that no additional description is believed to be required.

In the modified form shown in Fig. 6, the parts are the same as in Fig. 5 except that the lower end of slide 19 has a laterally projecting bracket 48 fixed thereto, the rearward end of which carries a downwardly extending externally threaded rod 49 that meshes with an internally threaded sleeve 50 which is mounted on a stud 51 set in the lower part of housing 24. The said sleeve carries a bevel gear 52 at its lower end which meshes with another bevel gear 53 that is fast on the shaft connected with hand crank 28.

It will be clear that the turning of hand crank 28 will rotate gear 53 which will in turn rotate gear 52 and connected sleeve 50, whereupon the coaction of the screw threads will cause threaded rod 49 to be raised or lowered according to the direction of rotation and to carry slide 19 with it. This movement of the slide will be transmitted to the parts at the opposite side of the window frame as described in the form shown in Fig. 5.

Turning now to the form of apparatus shown in Fig. 7, it will at first be noted that cross shaft 11 and its connected parts are entirely omitted. This form has a worm and worm gear arranged and operated as in the form shown in Figs. 1 to 4 inclusive, but the worm gear has fixed thereto a power arm 54 that has its extremity pivoted to a link 55 which is connected directly at 56 to slide 19. The swinging of power arm 54 by manual rotation of the worm and worm gear will raise and lower slide 19, and this movement is transmitted to slide 18 on the other side of the window frame through arms 29, 30 and their connection with the top of the rim of the lower window section. This elimination of the cross shaft 11, its mounting and connected parts provides a substantial economy in manufacturing cost.

In the modified form illustrated in Fig. 8 the parts are the same as in the form shown in Figs. 1 to 4 inclusive, except that the arms 29, 30 have their extremities fixedly pivoted in each side of the window frame as indicated at 57, while straps 33, 34 have their inner ends pivoted to the slides 18, 19, as indicated at 58.

In the operation of this modified form, the upward and downward movement of the slides causes the straps 33, 34 to swing the window sections around the fixed pivots 57 which act like hinge pivots, as distinguished from the combined sliding and swinging movement of the form shown in Figs. 1 to 4 inclusive.

The modified form shown in Figs. 9 and 10 has each window section secured by hinges 59 to each side of the front of the window frame, while curved straps 60 have their outer ends pivoted to each side of the window section rim near the upper part thereof, and their inner ends pivoted to slides 61, which are plain as distinguished from being slotted but move upwardly and downwardly in the window frame the same as slides 18, 19. This form operates by a plain hinge swinging movement, as in the case

of the form shown in Fig. 8, and the curving of straps 60 facilitates their function while permitting their inner ends to be moved upwardly and downwardly in a straight line and the complete housing of the straps within the window frame when the parts are closed.

Finally, the modified form shown in Figs. 11, 12 and 13 has the window frame 62 and the window section rim 63 composed of wood. Arms, one of which is shown and marked 64, are suitably secured to each side of the window section rim 63, as by screws 65, and their projecting ends are pivoted, as indicated at 66, to a pair of slides, one of which is shown and marked 67. The said slides are held in position on the window frame 62 by clips 68 which are fixed to the frame, as by screws 69. Two straps, one of which is shown and marked 70, are pivoted, as indicated at 71, to each side of the window section rim 63, being preferably pivoted directly to parts of the arms 64 that are fixed to the said section rim, and the outer ends of said strap 70 are pivoted, as indicated at 72, to the clips 68.

It will be clear that the arms 64 in this modified form correspond to the hereinabove described arms 29, 30; that the straps 70 correspond to the hereinabove described straps 33, 34; and that the slides 67 correspond to the hereinabove described slides 18, 19; and that the operation is the same as that described in connection with the form shown in Figs. 1 to 4 inclusive. As indicated in Fig. 11, there are spaces between the side window frame members and upper frame member to receive the arms 64 and the upper ends of slides 67 when the parts are closed. Also as shown in Figs. 11 and 12, the upper window frame member is provided with a recess 73 fitted to house the upper edge of the window section and provide better protection against the weather when the section is closed.

In regard to all the forms shown, I would note that any one of the kinds of manual actuating mechanism shown and described may be used in connection with any one of the kinds of window section mounting and connecting mechanism; so that I do not wish the fact that I have shown a certain form of one part of the mechanism with a certain form of another part of the mechanism to be understood as indicating that the features are not interchangeable in the way just described.

The structures herein represented combine efficiency with simplicity and economy in manufacture, and their practical and commercial advantages relate importantly to their adaptability for output on a large scale and installation as units during the construction of buildings without the necessity of departure from approved and standard parts and methods of construction generally adopted in the majority of building operations. The actuation of the parts requires no substantial exertion of strength. It is quiet, smooth and effective in operation and insures a rapid and wide opening as well as a rapid and tight closing which largely, if not entirely, eliminates rattling and leakage. I have previously mentioned that any suitable material may be used in forming the elements of this structure, although metal is preferred, and I may add that the construction lends itself well to an entire metallic unit with the best or appropriate metals selected for the different parts being left to the choice or judgment of the architect, designer, or manufacturer. Furthermore, as hereinabove indicated in connection with the form shown in Figs.

11, 12 and 13, the construction is adapted to the use of wood, plastics, molded fibrous materials and compositions or the like.

I desire it to be understood that various changes may be resorted to in the form, construction, material, and arrangement of the several parts without departing from the spirit and scope of my invention, and hence I do not intend to be limited to the details herein shown and described except as they may be included in the claims.

What I claim is:

1. A device of the character described comprising, a window section, a frame therefor, means securing the section to the frame, and mechanism for opening and closing the section by sliding and swinging motion, said mechanism including a slide mounted in one side of the frame, a pair of toggle links pivoted to each other and connected to said slide and to said frame, a power arm connected to the pivot of said toggle links, and means for moving said power arm to make and break the toggle.

2. A device of the character described comprising, a window section, a frame therefor, means securing the section to the frame, and mechanism for opening and closing the section by sliding and swinging motion, said mechanism including a slide mounted in one side of the frame, a pair of toggle links pivoted to each other and connected to said slide and to said frame, a power arm, a third link connecting said power arm with the pivot of said toggle links, and means for moving said power arm to make and break the toggle.

3. A device of the character described comprising, a window section, a frame therefor, means securing the section to the frame, and mechanism for opening and closing the section by sliding and swinging motion, said mechanism including a slide mounted in one side of the frame, a pair of toggle links pivoted to each other and connected to said slide and to said frame, a power arm connected to the pivot of said toggle links, means for moving said power arm to make and break the toggle, a second slide mounted in the other side of the frame, a second pair of toggle links connected to said slide and to said frame, and means interconnecting said pairs of toggle links to cause them to move in unison.

4. A device of the character described comprising, a window section, a frame therefor, means securing the section to the frame, and mechanism for opening and closing the section by sliding and swinging motion, said mechanism including a slide mounted in one side of the frame, a pair of toggle links pivoted to each other and connected to said slide and to said frame, a power arm, a third link connecting said power arm with the pivot of said toggle links, means for moving said power arm to make and break the toggle, a second slide mounted in the other side of the frame, a second pair of toggle links connected to said slide and to said frame, and means interconnecting said pairs of toggle links to cause them to move in unison.

5. A device of the character described comprising, a window section, a frame therefor, and mechanism for securing the section to the frame and imparting combined sliding and swinging motion to the section for opening and closing it, said mechanism including a slide mounted in the frame between the section and the frame, a pivot about which the section swings positioned in the

frame between the section and the frame, an operating element connected to the section and having a pivot positioned in the frame between the section and the frame, all of said mechanism being housed in the space between the section and the frame when the section is closed, and geared actuating means for reciprocating the slide in the frame to move one of said pivots toward and away from the other for opening and closing the section.

6. A device of the character described comprising, a window section, a frame therefor, and mechanism for securing the section to the frame and imparting combined sliding and swinging motion to the section for opening and closing it, said mechanism including a slide mounted in the frame between the section and the frame, a pivot about which the section swings positioned in the frame between the section and the frame, an operating element connected to the section and having a pivot positioned in the frame between the section and the frame, all of said mechanism being housed in the space between the section and the frame when the section is closed, and geared actuating means for reciprocating the slide in the frame to move said first named pivot toward and away from said last named pivot for opening and closing the section.

7. A device of the character described comprising, a plurality of window sections, a frame therefor, and mechanism for securing the sections to the frame and imparting combined sliding and swinging motion to the sections for opening and closing them, said mechanism including a slide mounted in the frame between the sections and the frame, pivots about which the sections swing positioned in the frame between the sections and the frame, operating elements connected to the sections and having pivots positioned in the frame between the sections and the frame, all of said mechanism being housed in the space between the sections and the frame when the sections are closed, and geared actuating means for reciprocating the slide in the frame to move certain of said pivots toward and away from the others for opening and closing the sections.

8. A device of the character described comprising, a plurality of window sections, a frame therefor, and mechanism for securing the sections to the frame and imparting combined sliding and swinging motion to the sections for opening and closing them, said mechanism including a slide mounted in the frame between the sections and the frame, pivots about which the sections swing positioned in the frame between the sections and the frame, operating elements connected to the sections and having pivots positioned in the frame between the sections and the frame, all of said mechanism being housed in the space between the sections and the frame when the sections are closed, and geared actuating means for reciprocating the slide in the frame to move said first named pivots toward and away from said last named pivots for opening and closing the sections.

9. A device of the character described comprising, a window section, a frame therefor, and mechanism for securing the section to the frame and imparting combined sliding and swinging motion to the section for opening and closing it, said mechanism including a slide mounted in the frame between the section and the frame, a pivot about which the section swings positioned in the frame between the section and the frame,

an operating element connected to the section and having a pivot positioned in the frame between the section and the frame, said pivots being located rearwardly of the longitudinal center of the slide, all of said mechanism being housed in the space between the section and the frame when the section is closed, and geared actuating means for reciprocating the slide in the frame to move one of said pivots toward and away from the other for opening and closing the section.

10. A device of the character described comprising, a window section, a frame therefor, and mechanism for securing the section to the frame and imparting combined sliding and swinging motion to the section for opening and closing it, said mechanism including a slide mounted in the frame between the section and the frame, a pivot about which the section swings positioned in the frame between the section and the frame, an operating element connected to the section and having a pivot positioned in the frame between the section and the frame, said pivots being located rearwardly of the longitudinal center of the slide, all of said mechanism being housed in the space between the section and the frame when the section is closed, and geared actuating means for reciprocating the slide in the frame to move one of said pivots toward and away from the other for opening and closing the section.

11. A device of the character described comprising, a plurality of window sections, a frame therefor, and mechanism for securing the sections to the frame and imparting combined sliding and swinging motion to the sections for opening and closing them, said mechanism including a slide mounted in the frame between the sections and the frame, pivots about which the sections swing positioned in the frame between the sections and the frame, operating elements connected to the sections and having pivots positioned in the frame between the sections and the frame, said pivots being located rearwardly of the longitudinal center of the slide, all of said mechanism being housed in the space between the sections and the frame when the sections are closed, and geared actuating means for reciprocating the slide in the frame to move certain of said pivots toward and away from the others for opening and closing the sections.

12. A device of the character described comprising, a plurality of window sections, a frame therefor, and mechanism for securing the sections to the frame and imparting combined sliding and swinging motion to the sections for opening and closing them, said mechanism including a slide mounted in the frame between the sections and the frame, pivots about which the sec-

tions swing positioned in the frame between the sections and the frame, operating elements connected to the sections and having pivots positioned in the frame between the sections and the frame, said pivots being located rearwardly of the longitudinal center of the slide, all of said mechanism being housed in the space between the sections and the frame when the sections are closed, and geared actuating means for reciprocating the slide in the frame to move one of said pivots toward and away from the other for opening and closing the section.

13. A device of the character described comprising, a plurality of window sections, a frame therefor, and mechanism for securing the sections to the frame and imparting combined sliding and swinging motion to the sections for opening and closing them, said mechanism including a slotted slide mounted in the frame between the sections and the frame, pivots about which the sections swing positioned in the frame between the sections and the frame, operating elements connected to the sections and having pivots positioned in the frame between the sections and the frame, said last named pivots passing through the slot in said slide to enter the frame and all of said mechanism being housed in the space between the sections and the frame when the sections are closed, and geared actuating means for reciprocating the slide in the frame to move one of said pivots toward and away from the other for opening and closing the sections.

14. A device of the character described comprising, a plurality of window sections, a frame therefor, and mechanism for securing the sections to the frame and imparting combined sliding and swinging motion to the sections for opening and closing them, said mechanism including a slotted slide mounted in the frame between the sections and the frame, pivots about which the sections swing positioned in the frame between the sections and the frame, operating elements connected to the sections and having pivots positioned in the frame between the sections and the frame, said last named pivots passing through the slot in said slide to enter the frame and all of said pivots being located rearwardly of the longitudinal center of the slide, all of said mechanism being housed in the space between the sections and the frame when the sections are closed, and geared actuating means for reciprocating the slide in the frame to move one of said pivots toward and away from the other for opening and closing the section.

GIUSEPPE GARGIULO.
